(57) **CLAIM**

The ornamental design for an airport visor, as shown and described.

DESCRIPTION

FIG. 1 is a top view of an airport visor showing my new design;

FIG. 2 is a bottom view of the airport visor shown in FIG. 1; FIG. 3 is a front view of the airport visor shown in FIG. 1, the rear view being a mirror image thereof;

FIG. 4 is a left side view of the airport visor shown in FIG. 1, the right side view being a mirror image thereof;

FIG. 5 is an isometric view of the airport visor of FIG. 1, but with the visor flexed for attachment to an airport; and, FIG. 6 is an isometric view of the airport visor of FIG. 1, the airport visor being shown in its environment attached to an exemplary airport.

The broken line showing of text on the airport visor, and the broken line showing of an exemplary airport, provide environment and form no part of the claimed design.
